JOINT LOCK HAMMER

Arthur M. Erickson, 1413 Jackson St., Seattle, Wash.
Filed May 23, 1962, Ser. No. 197,825
13 Claims. (Cl. 113—54)

This invention relates to a hammer and more particularly to a power hammer designed to close a sheet metal joint commonly known in the trade as a "Pittsburgh lock."

It is a general object of this invention to provide such a hammer which is of simple and economical, and yet durable construction, which is adapted to operate easily and efficiently on either heavier or lighter gauge sheet metal, and which will close such a metal joint without scuffing or otherwise damaging the sheet metal surface, and without distorting or bending the metal which forms the joint or which is adjacent thereto.

It is a further object to provide such a hammer which is readily adapted to be made as an attachment to any number of standard prior art rotary power tools, such as a portable bench grinder.

Other more particular objects and advantages of the invention will, with the foregoing, appear and be understood in the course of the following description and claims, the invention consisting in the novel construction and in the adaptation and combination of parts hereinafter described and claimed.

In the accompanying drawings:

FIGURE 1 is a fragmentary front elevational view showing a hammer made in accordance with my invention, the hammer being shown in operating position to bend over the "outstanding edge" of one metallic sheet so as to lock the joint;

FIG. 2 is a fragmentary view, drawn to an enlarged scale and taken on line 2—2 of FIG. 1, thus showing the hammer in side elevation and showing the sheet metal joint in section;

FIG. 3 is a side view of one embodiment of my invention, with the side cover of the housing removed to show the working parts therein;

FIG. 4 is a fragmentary sectional view taken on line 4—4 of FIG. 3 and drawn to an enlarged scale;

FIG. 5 is a view similar to FIG. 3, but showing a second embodiment of my invention;

FIG. 6 is a view similar to that of FIG. 5, but showing yet another embodiment of my invention; and

FIG. 7 is a fragmentary sectional view taken on line 7—7 of FIG. 6.

It is believed a clearer understanding of the nature, operation, and advantages of my invention will be attained by first describing in some detail the Pittsburgh lock and the manner of closing the same, and commenting briefly on the prior art machines devised to accomplish this operation and the difficulties encountered in the use of such prior art machines.

The Pittsburgh lock has long been used widely in the sheet metal industry in fastening opposite edges of one sheet of metal together, or two edges of different sheets of metal together, at a corner line of a duct or other structure. The sheets to be joined each have their edge portion prefabricated in a particular manner. One such sheet 10 has its edge portion bent at a right angle to form a downturned flange portion 11, this sheet being designated as the angled sheet. The other sheet 12, called the replaited sheet, has its edge portion folded back on itself to form a flat S fold, the inner, middle and outer portions of this fold being designated 13, 14 and 15, respectively. The middle and outer folds 14 and 15 are spaced slightly one from another to form an upwardly facing channel or groove 16 to receive the downturned flange 11. The outer fold 15 has its upper end portion extending beyond the

2

folds 13 and 14 to form an upstanding flange 17, commonly called the "outstanding edge." In forming the Pittsburgh lock, the downturned flange 11 is inserted into the channel 16, and then the outstanding edge 17 of the replaited sheet 12 is folded flat against the portion of the angled sheet 10 just inside the bend along a seam line 18. This completes or closes the lock so as to hold the two sheets together.

Clearly, manually hammering the outstanding edge 17 against the angled sheet is a time-consuming and hence inefficient operation. To perform this function mechanically, the prior art offers a number of devices. Some of these are designed to ride along the seam of the joint and press the outstanding edge into its lock position. Others have a reciprocating hammer motion and have the hammer head formed with its contact surface so curved that as the hammer is moved progressively along the seam, different portions along the hammer surface will pound any one portion of the outstanding edge over by increments.

The difficulties encountered with the prior art devices are several. Aside from the fact that most of the devices are unduly complex and hence too expensive for the more limited needs of many users, a good number of these are designed for only a relatively limited range of metal thicknesses. Thus if used on too heavy a metal, the machine is simply underpowered, and if used on too light a metal, the metal around the jointed area is bent or pounded out of shape. Another problem, which is encountered especially with machines having a reciprocating hammering motion, is that a machine which is small enough and light enough to be used conveniently by one man, is often not sturdy enough to endure extended and hard usage without requiring a good deal of expensive maintenance. Also in many of these machines, if not used skillfully, the galvanized finish, especially on the outstanding edge, becomes scuffed, besides causing the metal near the joint to become bent or distorted.

Thus the apparatus of the present invention was devised to accomplish the aforesigned objects of the invention so as to solve these problems.

Referring to the accompanying drawings, a standard prior art rotary tool, such as a bench grinder, is shown schematically at 20, this tool having a nose portion 21 with a power driven shaft 22 extending laterally therefrom. The hammer portion 25 of my invention comprises a closed housing structure 23, having the general configuration of a shallow cylinder. The curved circumferential wall of this cylinder-like housing is designated 24, while the flat circular side plates are designated 26 and 27, respectively, the latter being removably secured to the curved wall 24 by means of bolts 28. Extending outwardly from the center of the side wall 26, is a boss 30, having a center opening 31, to accommodate the shaft 22 which is inserted therein. So that housing 23 may be rigidly secured to the rotary tool 20, an angle iron 32 is welded or otherwise secured to the housing, and is bolted, as at 35, to the rotary tool.

Carried in the housing 23 for rotary motion therein is a flat circular drive plate 34, having a diameter moderately less than that of the inside surface of the cylindrical housing wall 24. At evenly spaced intervals along the circumference of the plate 34, are a plurality of semi-circular pockets 36, each arranged to interfit loosely with a related one of an equal number of hard, metallic, spherical balls 37 of uniform size. An internally threaded nut 38 is welded or otherwise secured to the center of the plate 34, to provide a socket to receive the threaded end of the power shaft 22, so that the plate 34 may be rigidly secured thereto.

The inner surface of the cylindrical housing wall 24 is formed with a rounded circumferential groove 40, having

a radius of curvature slightly greater than the radius of the balls 37. Thus as the plate 34 is rotated by the power shaft 22 within the housing 23, the balls 37, each in its related pocket 36, are caused to roll in a circular path within the race defined by this groove 40.

The lower end of the housing (i.e. the position of the portion of the housing furthest from the rotary tool 20) is formed with a re-entrant right angle cutout 41. The short side surface 42 of this cutout extends radially inward toward the center of rotation of the plate 34 (the plane of this surface thus being at right angles to the circumferential path of the groove at this point), and extends into the groove 40 to a distance substantially less than the radius of any one of the balls 37. The long side surface 43 of this cutout extends from the inner edge 44 of the surface 42 at right angles thereto, the direction of this extension being the same direction of travel of the plate 34 at this point. The effect of forming such a cutout is that as the balls 37 pass thereover each ball moves into the cutout by passing through the plane of the cutout surface 42, in a manner that the outer portion 45 of each ball protrudes a short distance into this cutout (i.e. beyond the plane defined by the cutout surface 43). The width of the cutout 41 is less than the diameter of the balls to prevent the balls from escaping therethrough.

In operation, the housing structure 23 is secured to the rotary tool 20 by bolting the angle iron 32 to the rotary tool while slipping the power shaft 22 into the boss 30 through the opening 31. The side cover plate 27 is removed, and the rotary plate 34 is secured to the shaft 22 by rotating this plate so that the nut 38 (being welded to the plate) threads onto the end of the shaft. (The threads are so arranged that as the plate 34 rotates, the action of such rotation is to thread the nut 38 more tightly onto the shaft. A stop collar 46 is welded to the shaft 22 to limit the extent to which it threads into the nut 38.) The cover plate 27 is again bolted into place, and the hammer is ready for operation.

The downturned flange 11 of the angle sheet 10 is inserted into the channel 16 of the edge portion of the replaited sheet 12 with the outstanding edge 17 reaching above the top surface of the angle sheet 10. Initially, a portion of the outstanding edge 17 (preferably an end portion) is manually or otherwise turned down over the angle sheet 10. The hammer is then positioned with the shorter surface 42 of the cutout 41 bearing against the upper vertical portion of the outer fold 15. Thus the apex line 44 of the cutout surfaces 42 and 43 coincides with the bend line 18 of the downturned end portion of the outstanding edge 17. The hammer is then tilted to a moderate degree away from the intended direction of travel (as shown in FIG. 1) and then moved along the length of the joint. As the balls 37 roll by the cutout 41, each ball impinges on the outstanding edge 17 so as to fold the outstanding edge against the sheet 10. It will be noted that the lower point of each ball passes very close to the plane of the top surface of the outstanding edge 17 after it has been folded into its closed position. The effect of this is that the outstanding edge portion 47 immediately in front of the path of travel of the hammer, by virtue of the edge portion immediately adjacent being folded over, is caused to be bent a moderate distance toward its fold position. That is to say, by the time the hammer actually reaches any one portion of the outstanding edge, that portion has already been folded over to some degree.

Because of the rolling action of the balls moving along the inner race 40, there is no scuffing action on the exposed surface of the outstanding edge 17. Unless the metal is of an unusually heavy gauge relative to the size of the tool being used, one pass is generally sufficient to lock the joint securely.

FIG. 5 shows a second embodiment of my invention wherein the plate 34 is replaced by a member 48 having four equally spaced radial arms 49 each of which causes a

related one of four balls 37 to travel along the race 40.

FIG. 6 is yet another embodiment wherein there are two arms 50 which similarly cause two balls 37 to travel along the outer race 40. The manner of assembling and mounting and the mode of operation of the second and third embodiments are the same as in the first embodiment.

It is believed that the invention will have been clearly understood from the foregoing detailed description of my now-preferred illustrated embodiments. Changes in the details of construction may be resorted to without departing from the spirit of the invention and it is accordingly my intention that no limitations be implied and that the hereto annexed claims be given the broadest interpretation to which the employed language fairly admits.

What I claim is:

1. A hammer to fold over the outstanding edge of a metal joint in a manner to close the joint, said hammer comprising:
  - (a) a housing defining a continuous annular race,
  - (b) at least one contact member arranged for travel along said race and constrained in a circular path by said race,
  - (c) a cutout in said housing to expose a portion of said race in a manner that said contact member will protrude into said cutout as it travels along said race, and
  - (d) drive means in said housing to cause said contact member to travel along said race, whereby the hammer may be located in a manner that said outstanding edge reaches into said cutout, causing the contact member to impinge on said outstanding edge so as to fold said edge into locked position.
2. The hammer as recited in claim 1, wherein said contact member is symmetrical about an axis so that said member is caused to roll along said race.
3. The hammer as recited in claim 1, wherein said contact member is a spherical ball and said race is defined by the inner surface of a cylindrical wall of said housing.
4. The hammer as recited in claim 3, wherein said drive means is a member mounted in said housing for rotary motion therein, said rotary member acting to contact said ball and push said ball along said race.
5. A hammer to fold over the outstanding edge of a metal joint in a manner to close the joint, said hammer comprising:
  - (a) a housing having a cylindrical wall, the inner surface of which defines a circumferential race,
  - (b) a cutout in said housing, said cutout extending into the path of said race,
  - (c) a plurality of rolling members carried in said housing and arranged to travel a circular path along said race in engagement therewith,
  - (d) a drive member mounted for rotary motion in said housing, the center of rotation of said drive member being on the center axis of said cylindrical wall, said drive member acting to contact said rolling members so as to cause said rolling members to travel along said race, and
  - (e) power means to rotate said drive member, so that by locating said housing with the outstanding edge in said cutout, said rolling members are caused to impinge on said outstanding edge so as to fold said edge over to lock the joint.
6. The hammer as recited in claim 5, wherein said drive member is a plate having a plurality of circumferential pockets, each pocket to receive a related one of said rolling members.
7. The hammer as recited in claim 5, wherein said drive member has a plurality of arms, each of said arms to engage a related one of said rolling members.
8. The hammer as recited in claim 5, wherein said power means is a rotary power tool having a drive shaft to turn said drive member, said housing having means by which said housing is fastened to said rotary tool.

9. The hammer as recited in claim 5, wherein said cutout has a surface the plane of which is at substantially right angles to the path of said race, so that by causing said cutout surface to bear against the joint surface below the outstanding edge, said hammer properly is located with respect to said joint so that the outstanding edge may be properly folded to close the joint.

10. The hammer as recited in claim 9, wherein said race is a rounded groove, and each of said rolling members is a spherical ball arranged to roll in said groove.

11. A joint lock hammer comprising:

- (a) a housing defining an annular race on the inside surface thereof,
- (b) at least one contact member located in said race in engagement therewith,
- (c) means to move said member along said race,
- (d) and a cutout in said housing intersecting said race and adapted to receive a portion of a sheet metal joint in the path of said contact member.

12. The hammer according to claim 11 wherein:

- (a) said cutout is in substantially right angular form,
- (b) said cutout having a short side extending radially with said annular race, and extending into said race a distance less than the thickness of said contact member,
- (c) and a long side extending in the direction of travel of said contact member.

5

13. A hammer for closing a Pittsburgh lock between an angled sheet-metal member and a replaited sheet metal member having an outstanding edge comprising:

- (a) a housing having a continuous annular groove on the inside surface thereof forming a circular race,
- (b) a cutout in the outside surface of said housing and intersecting said groove and adapted to receive a bent portion of said outstanding edge,
- (c) at least one contact member positioned for travel in said groove in engagement therewith,
- (d) means in said housing to move said contact member in said groove,
- (e) whereby said contact member impinges against the surface of said outstanding edge located in said cutout to fold the same against the outside surface of said angled sheet-metal member.
